UNITED STATES PATENT OFFICE.

GEORGE F. READ, OF NEW YORK, N. Y., ASSIGNOR TO ROBERT HOE, OF NEW YORK, N. Y.

PRINTING-MACHINE.

SPECIFICATION forming part of Letters Patent No. 758,690, dated May 3, 1904.

Application filed February 21, 1903. Serial No. 144,396. (No model.)

To all whom it may concern:

Be it known that I, GEORGE F. READ, a citizen of the United States, residing at New York, county of Kings, and State of New York, have 5 invented certain new and useful Improvements in Printing-Machines, fully described and represented in the following specification and the accompanying drawings, forming a part of the same.

10 This invention relates to certain improvements in associating and delivery mechanisms for printing-machines.

In the printing of certain kinds of publications, and particularly in magazine-work, it is 15 desirable that the machine be so constructed that it can deliver different kinds of products. On account of the conditions governing the sale of magazines or similar publications and to prevent what is known as "resale," it is 20 desirable that the pages of the magazine which form the body and contain the reading matter be connected either at the top or sides. Ordinarily in magazine-work and similar publications the signatures consist of sixteen pages, 25 eight of these pages being inserted and folded within the other eight, with the longitudinal folds coinciding. Such signatures are usually produced by subjecting associated webs to the action of a longitudinal folder. Where, however, 30 the pages of the magazine contain heavily-inked cuts, it is desirable to avoid, so far as possible, passing the associated webs over longitudinal-folding devices, because the ink on the heavy cuts on one web is liable to off-set to the adjoining web. When, therefore, 35 certain pages of the magazine are to contain heavy cuts, it is preferable to subject the webs containing these pages separately to the action of the longitudinal-folding devices and to

40 thereafter assemble the folded product so that the longitudinal folds produced in the webs instead of coinciding will when the webs are brought together be alongside each other. This method instead of producing sixteen 45 pages consisting of eight pages inserted and folded within the other eight by longitudinal folds which coincide will produce sixteen pages in which eight pages are formed by one

longitudinal fold and eight pages formed by another longitudinal fold, the longitudinal 50 folds lying alongside each other when the webs are brought together. Advertisers, however, insist that the advertising pages of the magazine or similar publication shall not to be connected at the fold-line, but shall be separated, 55 so that they can be readily inspected. It follows, therefore, that in printing the ordinary magazine the machine should be arranged so at to produce products consisting of sixteen pages folded and connected as above indicated—that is, with the longitudinal-fold lines coinciding—and also products of sixteen pages folded, as above indicated, with their longitudinal-fold lines lying alongside each other, and products in which the pages are not connected at their outer edges. It is also desirable in order to facilitate the removal of packs 60 of assembled sheets, whether the same be folded together or not, to deliver successive packs at separate points. When, therefore, the forms 65 of the machine are arranged so that packs of sheets are produced which contain different subjects-matter, it is possible to deliver the packs which contain the different subjects-matter at different points. If the packs 70 containing the same subject-matter be delivered at different points, successive packs can be spaced out slightly, so that it is easier to remove them, and congestion at the different delivery-points is avoided. 75

It is one of the objects of this invention to produce an improved associating and delivery mechanism for printing-machines in which mechanisms are provided for producing different kinds of product with respect to the 85 arrangement of the pages of the publication which is being printed.

A further object of the invention is to produce an improved delivery mechanism by which successive packs of sheets may be delivered at different points. 90

A further object of the invention is to generally improve certain features of construction of printing-machine deliveries.

With these and other objects in view the invention consists in certain constructions and 95

in certain parts, improvements, and combinations, as will be hereinafter fully described and then specifically pointed out in the claims hereunto appended.

5 In the accompanying drawings, Figure 1 is a front elevation of the machine. Fig. 2 is a top plan view illustrating the various sets of turner-bars which may be employed. Fig. 3 is a side elevation, partly in section, of the 10 construction shown in Fig. 1. Fig. 4 is a detail sectional view illustrating the construction by which the adjustments of the folders and coöperating rolls may be had. Fig. 5 is an enlarged front elevation of the sheet for- 15 warding and delivery cylinders.

Referring to the drawings, which illustrate one complete embodiment of the invention, the frame of the machine, which may be of any usual character, is marked 1. The web, 20 which is marked W, may be printed on any desired kind of printing-machine and from any desired arrangement of forms. The mechanism which forms the subject of this invention is, however, particularly well adapted for 25 use in fast rotary printing-machines, and the forms will preferably be arranged with the columns parallel to the axis of the cylinder. This mechanism is also well adapted for use with machines in which the cylinders carry 30 thirty-two forms, the forms being arranged in rows of four across the cylinder, with the columns, as before stated, parallel to the axis of the cylinder, although any desired number and arrangement of forms may be used.

35 In the construction illustrated the web having four printed pages abreast is advanced and is subjected to the action of a slitting mechanism, which may be located at any suitable point in the machine. As shown, this slitting 40 mechanism consists of wheels 2, and in the machine selected to illustrate the invention three such wheels are employed. These wheels 2 are mounted on arms 3, carried on a cross-rod 4, supported in standards 5, rising from 45 the frame of the machine. The usual roll 6 for coöperating with the slitters is provided, said roll being driven by a pair of miter-gears 7 8, the gear 7 being mounted on the shaft of the roll 6 and the gear 8 on a longitudinally- 50 arranged shaft 9, which is supported in brackets 10 and 11, the bracket 10 being supported on the standard 5 and the bracket 11 being mounted on the frame. The driving mechanism for this shaft 9 will be hereinafter 55 described, and it may be here remarked that the slitting mechanism in itself is of a well-known form and that any other suitable form of slitter may be substituted therefor, if desired.

The machine shown is constructed to produce 60 a variety of products, which will be varied according to the character of the matter contained in the printed pages, and the number of slitters will be varied according to the kinds of products which it is desired to produce. 65

In the preferred form of the construction the machine will be provided with two sets of longitudinal-folding devices, which may be of any desired description. Preferably, however, these folding devices will consist of the 70 ordinary longitudinal folders, said folders being marked 12 and 13 in the drawings. As shown, these folders consist of triangularly-arranged bars, the sets of bars being secured to plates 14, which are supported on pairs of 75 arms 15, which are pivoted on a cross-rod 16, which is in turn supported in suitable ears 17 on a standard 18. Coöperating with the folder 12 is the usual pair of nipping-rolls 19, and coöperating with the folder 13 is a similar 80 pair of nipping-rolls 20. Above the longitudinal folders there is located the usual guide-roll 21, said roll being mounted on a shaft 22 and provided with a miter-gear 23, which is in mesh with a similar gear 23', mounted 85 on the shaft 9, before referred to. When both longitudinal folders are employed, the webs after being subjected to the action of these folding devices are brought together, this being accomplished in the construction 90 shown by a pair of guiding and drawing-off rolls 24, said rolls being shown as located, as is usual, below the longitudinal folders.

In the preferred construction devices will be provided to adjust the longitudinal-folding 95 devices to the margin of the webs being printed. The adjusting devices may be of any desired construction. As shown, however, the standard 18 is mounted on a carriage which consists of side rails 25 and end rails 25'. This 100 carriage rests upon two cross-rails 26, which are connected by end rails 26', these cross-rails and end rails in reality forming a part of the frame of the machine. This carriage is also provided with suitable bearings 27, in 105 which the rolls 19 are mounted, and suitable bearings 28, in which the rolls 20 are mounted. It may be here remarked that the standard 18 also supports a pair of adjustable steady- 110 rods 29, by which the angle of the folders is determined and by which the folders are securely held in position. The shafts of the rolls 19 are provided with a pair of intermeshing 115 gears 30, and the shafts of the rolls 20 are provided with a similar pair of gears 31. Between these pairs of gears 30 and 31 are driving-gears 32 and 33, mounted on studs 34, supported in a cross-bar 35, which forms a cross- 120 web for the standard 18. With the construction described when it is desired to adjust the folders the carriage 25 is given an endwise movement, which may be accomplished by any suitable means. As shown, one of the end 125 bars 25' of the carriage supports a screw-shaft 36, which is provided with a hand-wheel 37, this screw-shaft being in engagement with a nut 38, (see dotted lines in Fig. 1,) said nut being mounted on a bracket 39, which is carried on one of the end bars 26'. It will be seen, therefore, that by turning the hand- 130

wheel the carriage, the folders, the drawing-rolls, and driving devices can be shifted with relation to the run of the web so as to bring the folders into proper relation to the margins.

It is also desirable that the guiding and drawing-off rolls 24 be capable of being adjusted to bring the webs which come together therein into proper register with each other.

10 The adjustment of the drawing-off rolls may be effected in any suitable manner. As shown, the shafts which carry these rolls 24 are journaled in suitable bearings 40, which are secured to the side bars 41 of a carriage, the 15 ends of which are formed by bars 42. The bars 41 are grooved to engage with tongues 43, formed on the cross bars or rails 26, so that the carriage may be slid on the rails to adjust the position of the rolls 24. The movement of 20 the carriage may be effected in any desired way; but in the construction shown there is provided a screw-shaft 44, which works in a threaded opening in one of the bars 42. This shaft is supported in one of the bars 26 and 25 is provided with a hand-wheel 45, by which the adjustment can be made.

The means for cutting the sheets from the webs and for delivering the sheets may be of any suitable character. As shown, this mechanism includes a pair of forwarding-cylinders 46 47, which in the construction shown carry the cutting devices, although the cutting devices may be otherwise mounted. In the preferred form of the construction and as shown 35 there will be four sets of cutting devices, which may be variously arranged upon the cylinders when they are mounted upon the cylinders. In the construction shown the cylinder 46 is provided with knives and knife-blocks 48 and 49 and with cutting-blocks 50 and 51, and the cylinder 47 is provided with two cutting-blocks 52 and 53 and two knives and knife-blocks 54 and 55, the cutting-blocks 52 and 53 being arranged to coöperate with the knives 48 and 49 and the cutting-blocks 50 and 51 being arranged to coöperate with the knives 54 and 55.

It is desirable that the delivery mechanism be of such a character that the various products may be delivered at different points. It may happen, especially when cylinders having thirty-two forms are employed, that the printed matter will form four signatures or packs of sheets, each consisting of sixteen 55 pages, and that each pack of sixteen pages will contain different subject-matter. In such a case it is desirable to deliver the packs containing the same subject-matter at the same point, so that the signatures may be readily assembled by taking a pack from each point. Furthermore, even when the packs of sheets do not contain different subject-matter it is desirable under certain circumstances to deliver the packs at different points, especially where the 60 product is being very rapidly delivered, thus

rendering it easier to remove the packs and avoiding congestion at the different points. In the present construction provision is made for delivering the products at four points, one half the product or packs of sheets cut 70 from the webs being taken by the cylinder 46 and the other half being taken by the cylinder 47. It follows, therefore, that in the present arrangement each cylinder must be provided with two sets of sheet-taking devices. 75 These devices may be of any desired construction. As shown, the cylinder 46 is provided with two sets of side grippers 56 and 57, and the cylinder 47 is provided with two similar sets of grippers 58 and 59. It is of course to 80 be understood that any other grippers or pins might be used instead of the side grippers; but when side grippers are used they may be operated by any desired mechanism. The grippers shown are alike in their construction 85 and operation, so that a description of one of them will suffice for all. Referring to the gripper 58, for instance, it consists of a small bell-crank pivoted at 60, one of the arms of the bell-crank forming the gripper-finger proper 90 and the other arm being connected by a link 61 to an operating-lever 62, which is pivoted on a stud 63, located on the end of the cylinder. The gripper is opened by means of a cam 64, suitably located on the frame of the 95 machine, the cam operating on a bowl 65, mounted on one end of the lever 62.

The sheets on the cylinders 46 and 47 might be delivered flat, if desired; but when they are to be folded off, since each cylinder is to take 100 two packs of sheets, a folding-off device will be provided for each set of grippers, which may be of any suitable construction. As shown, the folding-off devices consist of tucking-blades 66, 67, 68, and 69. These blades are 105 of a construction well-known in the art and are operated in the usual manner, so that a description of them is unnecessary.

The devices for receiving the folded sheets from the cylinders 46 and 47 may be of any 110 suitable description. As shown, there are provided four sheet-receiving cylinders 70, 71, 72, and 73. These cylinders are mounted on suitable shafts supported in the frame. The cylinders 70 and 71 take the folded sheets from the blades 66 and 67, respectively, and the cylinders 72 and 73 take the sheets from the blades 69 and 68, respectively. Each of these cylinders 70, 71, 72, and 73 is provided with a suitable means for taking the folded sheet. As 115 shown, these sheet-taking means consist of nipper-jaws 74, 75, 76, and 77. The nipper-jaws illustrated are of an ordinary type well-known in the art, and a specific description of them is unnecessary.

Any suitable means may be provided for receiving the folded sheets from the cylinders 70, 71, 72, and 73. As shown, four sets of traveling belts are employed for this purpose, these belts being marked 78, 79, 80, and 81. 120 125 130

Suitable stripping devices 82, 83, 84, and 85 may, if desired, be employed with the cylinders 70, 71, 72 and 73 to insure certain delivery of the folded sheets from the cylinders.

The gearing for driving the several parts may be of any desired type. As shown, the power-shaft of the machine, (see Fig. 1,) which is marked 86, drives through a train of gears (indicated in dotted lines in this figure) to the cylinder 47. The cylinders 46 and 47 are provided with intermeshing gears. (Not shown.) The shaft of the cylinder 46 is provided with a gear the pitch-line of which is indicated at 87, said gear driving an intermediate 88. (Indicated in dotted lines in Fig. 1.) The shafts of the rolls 24 are provided with intermeshing gears 89, and one of these gears meshes with a gear 90, which drives the gear 32, before referred to, these gears being part of the train by which the drawing-off rolls 19 and 20 are driven. It has been heretofore stated that the shafts of the cylinders 46 and 47 are provided with intermeshing gears. (Not shown.) The gear on the cylinder 46 drives the gears of a train, (marked 91,) which is located on the side of the machine, the upper gear of this train meshing with and driving a gear 91', which is located on the shaft 9, before referred to.

While the gearing which has been described is a convenient gearing, it is to be understood that any other desired arrangement may be employed for driving the several parts of the machine.

The incoming webs will be led in different ways, according to the product which is being printed in the machine. Assuming that it is desired to deliver a product consisting of sixteen sheets made up of two sets of eight sheets with their fold-lines adjacent and parallel, the two outside slitters 2 will be thrown out of action, and the web will be slit by the middle slitter 2. It will then be led by means of suitable guides—such, for instance, as the guides marked 92 and 93—to the roll 21, which is located above the longitudinal folders. From this roll each half of the web passes over its own folder and between the pairs of nipping-rolls coacting with its folder, after which the two halves of the web are brought together by means of the guiding and drawing-off rolls 24, from which point the assembled webs pass to the forwarding-cylinders 46 and 47. The first two sets of sheets will be taken by the grippers on the cylinder 46, and one of the sets will be taken by the delivery-cylinder 70 and the other by the delivery-cylinder 71. The packs of sheets on these cylinders are then delivered to the traveling tapes 78 and 79. The next two sets of sheets will be taken by the grippers on the forwarding-cylinder 47 and will be delivered by its delivery-cylinders to the tapes 80 and 81.

Assuming that it is desired to deliver products of eight sheets folded together, but not

connected at the top or sides—as, for instance, when the advertising-sheets of a magazine are being printed—all the slitters will be brought into action, so that the web will be divided into four parts or ribbons. After leaving the slitting-roll 6 the four parts or ribbons of the web may be led under the guides 92 and 93; but instead of being led from the guide 93 to the roller 21 above the folders the webs will be directed up, as indicated at W¹, to a suitable guide 95, which is mounted on the top of the machine-frame. From this point in a machine embodying the preferred construction two of the parts of the web will be sent over turner-bars 96 and 97 to guides 98 and 99, and the other two parts of the web will be sent over turner-bars 100 and 101 to guides 102 and 103. These turner-bars operate to superpose the webs in the usual manner. From the guides 98 99 the webs may be led by any suitable arrangement of guides to a point where the four ribbons or parts will be associated. Two guides 104 105 are shown as located below the guides 98 and 99, and two guides 106 and 107 are shown as located below the guides 102 103. These guides are mounted in a usual manner, and the construction need not be specifically described. From these guides in the preferred form of the construction the parts of the web which pass over the guides 98 99 95 are led between the nipping-rolls 20 for the folder 13 and thence to the drawing-off rollers 24, the webs which pass over the guides 102 103 being led through the nipping-rolls 19 and thence to the rolls 24. The four parts 100 of the web will be associated by the rolls 24 and will pass to the cylinders 46 47, which operate in the manner before described, and these cylinders, together with their co-operating mechanism, deliver the sheets in packs of eight 105 sheets or sixteen pages folded together, but not connected at the top or sides.

Assuming that it is desired to deliver products of sixteen pages, consisting of two eight-page sheets, one of which is folded within the other and the fold-lines coinciding, the two outer slitters will be thrown out of operation, the middle slitter in this case operating to divide the web into two parts. One of the parts of the web after being slit may be led beneath 115 the guides 92 93, before described, and the other part of the web may be led down and under a guide 108, (see dotted lines in Fig. 3,) which is located beneath the slitting mechanism. From this guide 108 the part of the web referred to will be led over turner-bars 109 110, by which it is directed under the other part of the web, which, as before said, has been led directly under the guides 92 93. The two parts of the web are associated as they 125 pass under the guide 93 and thus associated are led over the roller 21 and over the folder 12, which imparts a longitudinal fold to them. From this point they are led, by means of the nipping-rollers 19 and the drawing-off rollers 130

24, to the cylinders 46 and 47 and are disposed of by these cylinders and their connected mechanism in the manner before described.

While the construction shown illustrates a preferred embodiment of the invention, it is to be understood that changes and variations may be made in the construction by which the invention is carried into effect. The invention is not, therefore, to be limited to the specific construction hereinbefore described.

What I claim is—

1. The combination with means for advancing a web, of means for dividing the web into two or four parts, a pair of longitudinal folders to which the web is led when it is divided into two parts, means for bringing together the parts of the web when it is divided into four parts, and sheet cutting and delivery mechanism, substantially as described.

2. The combination with means for advancing a web, of means for dividing the web into two or four parts, a pair of longitudinal folders to which the parts of the web are led when it is divided into two parts, means for associating two parts of the web with the other two parts when it is divided into four parts and for bringing together the webs thus associated, and sheet cutting and delivery mechanism, substantially as described.

3. The combination with means for advancing a web, of means for dividing the web into two or four parts, means for associating one part of the web with the other part when it is divided into two parts, a longitudinal folder, means for bringing together the parts of the web when it is divided into four parts, and sheet cutting and delivery mechanism, substantially as described.

4. The combination with means for advancing a web, of means for dividing the web into two or four parts, means for associating one part of the web with the other part when it is divided into two parts, a longitudinal folder to which the associated parts of the web are led, means for associating two of the parts of the web with the other two parts when it is divided into four parts, means for bringing together the associated webs, and sheet cutting and delivery mechanism, substantially as described.

5. The combination with means for advancing a web, of means for dividing it into two or four parts, a pair of longitudinal folders, means whereby each part of the web when it is divided into two parts may be led to a different folder or the two parts may be associated and led to one folder, means for bringing together the parts of the web when it is divided into four parts, and sheet cutting and delivery mechanism, substantially as described.

6. The combination with means for advancing a web, of means for dividing it into two or four parts, a pair of longitudinal folders, means whereby each part of the web when it is divided into two parts may be led to a different folder or the two parts may be associ-

ated and led to one folder, means for associating two of the parts of the web with the other two parts when it is cut into four parts, means for bringing together the associated parts of the web, and sheet cutting and delivery mechanism, substantially as described.

7. The combination with a pair of co-operating forwarding-cylinders each having a plurality of retaining devices, means for operating the retaining devices so that a part of the product passing between the cylinders will be taken by the retaining devices on one cylinder and the remainder of the product will be taken by the retaining devices on the other cylinder, and an independent product-receiving device for each retaining device, substantially as described.

8. The combination with a pair of co-operating forwarding-cylinders each having a plurality of retaining devices and cutting devices, means for operating the retaining devices so that part of the sheets cut from the web fed to the cylinders will be taken by the retaining devices on one cylinder and the remainder of the sheets will be taken by the retaining devices on the other cylinder, and an independent product-receiving device for each retaining device, substantially as described.

9. The combination with a pair of co-operating forwarding-cylinders each having a plurality of retaining devices, a plurality of folding-off devices and suitable cutting devices, of means for operating the retaining devices so that part of the sheets cut from a web fed to the cylinders will be taken by the retaining devices on one cylinder and the remainder of the sheets will be taken by the retaining devices on the other cylinder, means for operating the folding-off devices, and a sheet-receiving device for each sheet-retaining device into which the sheets are folded by the folding devices, substantially as described.

10. The combination with means for advancing a web, of means for dividing the web into two or four parts, a pair of longitudinal folders to which the web is led when it is divided into two parts, means for bringing together the parts of the web when it is divided into four parts, and a single delivery mechanism to which either product may be led, substantially as described.

11. The combination with devices for giving two separate webs a longitudinal fold, of means whereby each web may be led to a folding device, or whereby the webs may be associated and led to one of said devices, a pair of co-operating forwarding-cylinders, devices for severing the webs into sheets, retaining devices on each of the forwarding-cylinders, means for operating said devices so that those on one cylinder take a part of the sheets passing between the cylinders, and those on the other cylinder take the remainder of the sheets, and independent sheet-receiving means for each cylinder, substantially as described.

12. The combination with means for dividing a web into two or four parts, of longitudinal folding devices, means whereby the two parts of the web, when it is divided into two parts, may be associated and led to one of said folding devices, or whereby each of said parts may be led separately to a folding device, a pair of coöperating forwarding-cylinders, means for leading the web from one or both 5 of said folding devices to said forwarding-cylinders, means for leading the web when it is divided into four parts to said forwarding-cylinders, sheet-severing devices, retaining devices on each of the forwarding-cylinders, 10 means for operating said devices so that those on one cylinder take a part of the sheets passing between the cylinders, and those on the other cylinder take the remainder of the sheets, and independent sheet-receiving means 15 for each cylinder, substantially as described. 20
13. The combination with means for dividing a web into either two or four parts, of longitudinal folding devices, means whereby the two parts of the web, when it is divided into two parts, may be associated and led to one of said folding devices, or whereby each of said parts may be led separately to a folding device, a pair of coöperating forwarding-cylinders, means for associating two parts of the web 25 when it is divided into four parts with the other two parts, means for leading the web from one or both of the folding devices to the forwarding-cylinders, means for leading the web when divided into four parts to said cylinders, sheet-severing devices, retaining devices on each of the forwarding-cylinders, 30 means for operating said devices so that those on one cylinder take a part of the sheets passing between the cylinders, and those on the other cylinder take the remainder of the sheets, and independent sheet-receiving means 35 for each cylinder, substantially as described. 40
14. The combination with means for dividing a web into two or four parts, of a pair of longitudinal folders, means for directing the parts of the web when it is divided into two parts to said folders, turner-bars whereby the two parts of the web may be associated and 45
- led to one of the folders, sets of turner-bars for associating two parts of the web with the other two parts when it is divided into four parts, a pair of forwarding-cylinders to which the webs are led from the folders or the turner-bars, sheet-severing devices, retaining devices on each of the forwarding-cylinders, 50 means for operating said devices so that those on one cylinder take a part of the sheets passing between the cylinders, and those on the other cylinder take the remainder of the sheets, and independent sheet-receiving means 55 for each cylinder, substantially as described. 60
15. The combination with a pair of coöperating forwarding-cylinders, each having a plurality of sheet-retaining devices, of means for operating said devices so that those on one cylinder take a part of the product passing between the cylinders and those on the other cylinder take the remainder of the product, and two delivery-cylinders for each forwarding-cylinder, one cylinder receiving the product 65 held by one of said sheet-retaining devices and the other receiving the product held by the other of said sheet-retaining devices, substantially as described. 70
16. The combination with a pair of coöperating forwarding-cylinders, each having a plurality of sheet-retaining devices, of means for operating said devices so that those on one cylinder take a part of the product passing between the cylinder and those on the other 75 cylinder take the remainder of the product, two sets of folding-off devices on each forwarding-cylinder, two sheet-receiving cylinders coöperating with each forwarding-cylinder, one of said sheet-receiving cylinders receiving the product from one set of folding 80 devices and the other from the other set of folding devices, substantially as described. 85
- In testimony whereof I have hereunto set my hand in the presence of two subscribing witnesses. 90
